4 Claims. (Cl. 25—131)

1

In shuttering assemblies for moulding concrete buildings and structures in situ, it is known to provide sectionalised structures comprising a number of units each of general plate form, assembled edgewise to provide a common surface, and comprising separate tubular waling pieces characterised by stiffness against lateral bending included in the joints between the edges of adjacent panel rows, and crossing the joints of the assembly that are transverse to the rows. The present invention is concerned with this subject matter, and its object is to provide a waling member having specialised uses difficult or impossible to known waling members while remaining capable of carrying out most if not all of the functions of those members.

The most useful species of known tubular waling members are those comprising a tubular body and a flange extending away from the rear face of the assembly. The adjacent panel edges are grooved so as to provide between them when they are assembled edge to edge a cavity whose cross-sectional shape is that of the tubular body. Accordingly, as each row is erected and after the waling members are laid in position in the grooves preparatory to the erection of the next succeeding row of panels, the tubular body projects above the edges of the panels and constitutes the highest level of the assembly. Conversely, if an opening is left in the assembly, the tubular body of the waling member, above the opening, projects downwardly into the opening. At times it is necessary or desirable to have elements extending from the continuous face of the assembly, through the assembly to the opposite face. If the cross-sectional shape of such elements corresponds to or comprises a part corresponding to that of the waling member and the part is thin (for instance if the element is a sheet metal cross tie of appropriate shape), the projection of the tubular body above or below the joints between the panels is not disadvantageous, because the element can be laid over or under the waling member and included in the joint. But if the element is too thick for inclusion in the joint or does not conform to the cross section of the waling member, the projection of the tubular body above or below the panels is troublesome.

As an example, the element may be the frame of a door or window to be incorporated in a wall which is to be cast between parallel assemblies. Hitherto, it has been necessary to enclose the frame within the moulding cavity, so that, on demoulding, the architraves are flush with the cast wall. The plaster coating subsequently ap-

2

plied to the wall will leave the frames recessed, which is normally not desirable.

The main object of the present invention is to provide a waling member which has all the advantages of the waling members considered above, but which may also be modified at need to permit elements to be passed through the assembly.

According to the invention, a waling member is constructed in two parts detachably secured together and collectively forming a tubular body of the cross-section of which each part provides substantially one half.

Further according to the invention, each part 15 comprises a flange extending beyond the tubular body, the flanges of the two parts being overlapped and detachably secured together.

In one form of the invention, the flanges extend beyond the panels in the direction away 20 from the continuous face, and are bolted together there.

The parts may each also provide oppositely extending flanges which overlap and are included 25 in the joint between adjacent panels; and may further provide elements for anchoring the waling member to the panels between which it lies.

The particular advantage of the waling member of the invention is that, when the parts are assembled, the member is capable of carrying out 30 all the functions of the known tubular waling members mentioned above. When it is required to pass an element through the assembly, the two parts of the waling member are separated and only one part is used. When engaged with the 35 edges of the panels, the part in use is still a waling member in that it fulfills the function of aligning the panels, but it does so without presenting any significant projection above or below the panel edges as the case may be. Elements 40 such as door and window frames may then be assembled to project beyond the moulding cavity into or even through the panel assemblies. When thus assembled, the frames come into close contact with the panel edges or a flange of the waling 45 member over-lying said edges, so that the assembly is suitable to form the moulding wall.

The invention is illustrated by way of example in the accompanying drawings, in which:

Figure I is a perspective view of part of a waling member made in accordance with the invention;

Figure II is a sectional end view of two adjacent panels and a waling member engaged between the panels;

Figures III and IV are respectively a sectional

and a plan view of a known tubular waling member spanning an opening for a doorway, and in Figure III a door frame is shown in the casting cavity;

Figure V is a side view in the direction of the arrow in Figure III;

Figure VI is a fragmentary sectional view of one cast wall and part of the door frame;

Figure VII is a perspective view partly sectioned showing how the waling member of the invention is used in the neighborhood of an opening for a door;

Figure VIII is a fragmentary sectional view on the line VIII—VIII of Figure VII;

Figure IX is an end view partly in section showing how the waling member of the invention is used in the neighbourhood of a window frame, and

Figure X is a detail sectional view of a modified arrangement; and

Figure XI is a perspective view of a modified waling member.

Referring firstly to Figures III, IV and V, the waling members 2, which are known tubular waling members such as those mentioned above provide a tubular body 3, two flanges 4, 5 and additional flanges 6, 6 forming hooks which engage shoulders 7, 7 on the panels 8, 8.

The units 3, 4, 5, 6 of the members 2 are not separable.

If it is required to pass an element through or partly through the shuttering assembly, it is only possible to do so if the cross-sectional shape of the element corresponds, or comprises a portion corresponding, to that of the waling member 2; and further, if the element or the said portion of it is thin enough to be included in the joint. For example, a cross tie such as that designated 33 in Figure VII, of sheet metal, can be included in the joint and extend through the joint without interference with the shuttering. But if the element is thick or does not conform with the cross-sectional shape of the waling member, the tubular body 3 of the member, since it fills the space defined between the grooves 10 of the panel edges, prevents it from passing through or being included in the joint.

For example, such an element may be the frame of a door or window which is to be incorporated in a wall cast between parallel shuttering assemblies.

If an opening such as 11 (Figure V) were to be left in the shuttering assembly 12 for the frame, part 13 of the tubular body 3 of each waling member 2 would project into the opening. Satisfactory edge engagement between the door frame and the panel edges at the opening 11 would be impossible because of the projecting portion 13 of the waling member. Accordingly it is necessary to build the parallel shuttering assemblies without openings and to locate the door frames such as 14, and also window frames, within the moulding cavity 15, as in Figure IV. The frame 14 thus acts as part of the shuttering assembly and is cast into the walls 16 during the moulding operation.

The outer surfaces of the architraves 17 of the frame 14 are flush with the faces of the cast walls 16 and, when the latter are plastered, the architraves of the door and window frames are left recessed as is shown in Figure VI. This is not desirable because it detracts from the appearance of the completed building and also because the edges 16a of the plaster coat 16b are vulnerable to knocks and liable to be broken.

The waling member of the invention is shown in Figures I and II. It includes the two parts 18, 19 each provided with a depression 20 which is triangular in cross-section and two oppositely directed flanges 21, 22; and two Z-shaped elements 23, the limbs 24 of which overlap the flanges 21 and the limbs 25 of which are inwardly directed to act as hooks. The parts 18, 19 and the elements 23 are assembled with the flanges 21 and the flanges 22 overlapping and are detachably secured together by a series of bolts 26, which also secure the limbs 25 of the elements 23 to the flanges 21.

The waling member thus assembled is the equivalent of the known waling member 2 (Figure III) in that the parts 18 and 19 collectively provide substantially one half each of the cross-section of a tubular body 3a, and in that the flanges 21, 22 correspond to the flanges 4, 5 of the known waling member 2; while the elements 23 correspond to the flanges 6, 6. Like the flange 4 of the waling member 2, the flange 22 is just wide enough to reach the moulding face 27 of the panels 8 with which the waling member is engaged; whereas the flange 21, like the flange 5, projects beyond the rear face 28 of the panels. Its projection is, however, more pronounced to allow space for the bolts 26.

The waling member of the invention is able to carry out all the functions of a known waling member such as member 2 in that it aligns the panels 8 by being included within the joint between the adjoining edges, and in that it engages the shoulders 7 of the panels 8 to resist outward bulging of the panels during the moulding operation. Like the known waling members, it is engaged with the panels by relative rotation, as is more fully described in the specification of applicant's Patent No. 2,447,670, August 24, 1948.

However, the detachability of the two parts 18, 19 permits either part to be separately used, and to function as a waling member to align adjacent panels; while not presenting any obstructive projection above the edges of the panels it aligns, or below them as the case may be. This is illustrated in Figures VII to X. In Figure VII the panels 8 are assembled to provide an opening 28a, in face view, for a door frame 14a. The panels are assembled edgewise, and included in the horizontal joint 29 there is a member 30 which is one of the parts 18 or 19 of the waling member of the invention. The tongue formation 31 of the member 30 engages in the grooves 32 in the lower edges of the panels above the member and there is a cross tie 33 to hold the two shuttering assemblies (of which only one is shown) together.

Within the opening the door frame 14a is positioned. The upwardly directed face 34 of the architrave 17a is jointed with the under face of the flange 22a of the member 30, and the outwardly directed faces 35 of the architrave with the vertical edge faces 36 of the panels 8 at the sides of the opening.

As in the known method, the door frame 14a constitutes part of the shuttering, but in so far as it defines the moulding cavity, the portion 15a of the cavity behind the architrave is wider than the cavity between the panels 8. This is made possible by the butting engagement of the faces 34 and 22a, which permits the architrave 17a to extend beyond the plane of the moulding face 37 of the shuttering and into the opening 28a without impairing the efficiency of the shuttering assembly.

The face 38 of the cast wall 16a is thus recessed relatively to the face 34a of the architrave 17a, and, when the wall is plastered, the outer face of the plaster coat may be made flush with the face 34a, or even recessed.

In Figure IX the shuttering assembly is erected to leave an opening 28b, which receives a window frame 14b. In this case the member 30a is again one part 18 or 19 of the waling member of the invention, but it is arranged with its tongue 31a downward so as not to project into the opening 28b. At the upper vertical edge of the frame 14b, the aligning member (not shown) is again one half of the normal waling member, with its tongue upwards, as in Figure VII.

In order to centre the frame 14b within the opening angle, brackets 30b may be provided, the brackets being secured to the member 30a by the bolts 26a, and the limbs 30c of the brackets lying against the architraves of the frame 14b.

In Figure X, the sill 14c of the frame extends well beyond the panel assembly and the member 30a. In order to locate the frame relatively to the shuttering, an L-shaped bracket 30d is arranged with its limb 30e butting against the end face of the sill.

The use of the waling members of the invention avoids multiplication of the standard units employed to construct the shuttering assembly in that, at openings in the shuttering, the waling members at the horizontal edges of the openings are readily modified, to allow door and window frames to be built into the assembly, merely by detaching one of the two parts 18 or 19 of the members and using the other alone. To ensure that the complete waling member providing the tubular body 3a is present over substantially the entire horizontal extent of the panels themselves, one of the two parts of the member may be made in sections, so that only sufficient of such part need be detached to extend across the door or window frame. This construction is illustrated in Figure XI in which the part 18 is shown in sections. Since the member is reversible end for end, only one of the two parts and one of the two Z-shaped elements 23 need be sectioned.

I claim:

1. A waling member of the kind specified for longitudinal disposition in a joint between confronting edges of adjacent panel members; said waling member comprising two superposed parts formed with aligned portions defining a longitudinal tubular body, said portion of each part providing substantially one-half of the cross-section of said tubular body, each of said parts further being formed with a flange extending along an edge of said portion and having a width sufficient to project beyond a joint between adjacent panel members, said superposed parts being arranged with said flanges thereof in overlapped relationship, hooked anchoring means extending from at least one of said flanges for anchoring the waling member to at least one panel member adjacent thereto, and means detachably securing said flanges to each other and to said hooked anchoring means at locations adjacent the edges of the flanges for disposition beyond the joint between adjacent panel members.

2. A waling member according to claim 1; wherein said securing means are screw threaded

for easy detachment from said flanges and said anchoring means.

3. A waling member of the kind specified for longitudinal disposition in a joint between confronting edges of adjacent panel members; said waling member comprising two superposed parts formed with aligned portions defining a longitudinal tubular body, said portion of each part providing substantially one-half of the cross-section of said tubular body, one of said parts including a plurality of longitudinally separate sections, each of said parts further being formed with a flange extending along an edge of said portion thereof and having a width sufficient to project beyond a joint between adjacent panel members, said superposed parts being arranged with said flanges thereof in overlapped relationship, and screw threaded means detachably securing said flanges together at locations adjacent the edges of the latter and in each of said longitudinally separate sections of said one part for disposition beyond the joint between adjacent panel members, whereby any of said longitudinally separate sections may be independently detached from the remainder of said waling member.

4. A waling member of the kind specified for longitudinal disposition in a joint between confronting edges of adjacent panel members; said waling member comprising two superposed elongated parts formed with aligned portions defining a longitudinal tubular body, said portion of each part providing substantially one-half of the cross-section of said tubular body, one of said parts including a plurality of longitudinally separate sections, each of said parts further being formed with a flange extending along an edge of said portion thereof and having a width sufficient to project beyond a joint between adjacent panel members, said superposed parts being arranged with said flanges thereof in overlapped relationship, a hook shaped anchoring member extending along the flange of each of said parts, the anchoring member associated with said one part including longitudinally separate sections corresponding in length to said sections of the related part, and screw threaded means detachably securing said flanges to each other and to said anchoring members at locations adjacent the edges of said flanges and in each of said longitudinally separate sections of said one part and the associated anchoring member for disposition beyond the joint between adjacent panel members, whereby any of said longitudinally separate sections of said one part and of the associated anchoring member may be independently detached from the remainder of the waling member.

ROY WILLIAM RUMBLE.
